ARMATURE WINDING MACHINE

Robert L. Probst, Affton, Mo.

Application October 21, 1948, Serial No. 55,677

6 Claims. (Cl. 192—139)

1

This invention relates generally to armature winding machines, and, more particularly, to certain new and useful improvements therein.

The primary object of the present invention is to provide an armature winding machine provided with a unique mechanism by operation of which a predetermined number of turns of the armature to be wound may be automatically effected.

A further object of the present invention is to provide an armature winding machine having a transmission which is automatically disconnected upon the completion of a pre-selected number of revolutions of the armature to be wound.

An additional object of the present invention is to provide an armature winding machine provided with adjustable tension means for securely maintaining the armature in position during operation of the machine.

And with the above and other objects in view, my invention resides in the novel features of form, construction, arrangement, and combination of parts presently described and pointed out in the claims.

In the accompanying drawings (three sheets)—

Figure 1 is a front elevational view of an armature winding machine constructed in accordance with and embodying my invention;

Figure 2 is a top plan view of the armature winding machine;

Figures 3 and 4 are transverse sectional views taken along lines 3—3 and 4—4 respectively of Figure 1;

Figure 5 is a horizontal sectional view taken along line 5—5 of Figure 4;

Figures 6, 7, and 8 are fragmentary sectional views taken along lines 6—6, 7—7, and 8—8 of Figure 5;

Figure 9 is a fragmentary front elevational view of the setting mechanism;

Figures 10, 11, 12 and 13 are fragmentary sectional views all taken along line 10—10 of Figure 4 and respectively showing the transmission mechanism in its several different positions of operation.

Referring now in more detail, and by reference characters to the drawings, which illustrate a preferred embodiment of the present invention, A designates an armature winding machine supported upon a table 1 having secured thereon, at one end, a conventional prime mover 2 and, adjacent thereto, a housing 3 for a counter mechanism C. Said housing 3 is divided by a transversely extending wall 4 into forward and rear compartments, a, b, respectively (forward having

2

reference to the right end of the table 1 as shown in Figure 2).

The output shaft 5 of the prime mover 2 is provided at its end with a clutch-forming driving member 6 which is disposed within the compartment b of the housing 3 and a reduced portion 7 journalled suitably within the rear wall 8 of the housing 3. Disposed for optional engagement with the member 6 is a clutch-forming driven member 9 keyed upon one end of a shaft 10 journalled within the wall 4 by a ball bearing 11, the driven member 9 being integrally provided with an actuating spool 12 comprising spaced collars 13, 13'. Forwardly of the wall 4, the shaft 10 has keyed thereon a worm gear 14 for meshing engagement with a spur gear 15 keyed or otherwise rigidly mounted on a shaft 16 disposed in a plane perpendicular to the axis of the shaft 10.

The shaft 16 extends between and is journalled in the upstanding legs 17, 18 of a cradle or U-shaped bracket member 19 disposed within the compartment a. The leg 17 is pivotally supported by integral, aligned, projecting pins 20, 20' extending into suitable aligned apertures 21, 21' in opposite walls of the compartment a, and is further provided with a ball bearing 22 for supporting the shaft 16. The leg 18 of the cradle 19 extends partially through a relatively large, elongated aperture 23 provided in the front wall of the housing 3. At its outer end the shaft 16 projects beyond the leg 18 and is diametrically increased in the provision of an integral dial member 24 extending marginally beyond the forward and rear faces of the leg 18. On its outwardly presented face the dial member 24 is provided with a series of uniformly spaced apertures e. One of such apertures e is labeled or marked with a numeral "zero" and the other apertures e are similarly marked with numerals 40 "1", "2", "3" and so on in successive numerical order. The shaft 16 is diametrically reduced at its outer end in the formation of a tongue-like projection 24' having disposed thereon a freely rotatable knob 25 including a dial member 26 held in surface abutment against the outer face of the dial member 24 by means of a spring 26' encircling the projection 24' of the shaft 16 and endwise abutting against a shoulder 27 provided inwardly of a shank portion 28 of the knob 25 and against the inner face of an end stop 29 secured to the outer margins of the projection 24' by means of a screw 30.

The dial member 26 is provided with a single window-like aperture g, and is further provided 55 adjacent its outer periphery with a pin 31 which

projects inwardly parallel to the shaft 16. The pin 31 is of substantially the same diameter, and is located at the same radial distance from the center line of the shaft 16, as the aperture e so as to fit snugly into and project through any selected one of them for stop-forming abutment along its inwardly projecting end against the forwardly presented lateral face of the cradle leg 18. In this connection it should be noted that the pin 31 is of such length that it will be fully withdrawn from engagement with the selected aperture e when the knob 25 is manually pulled outwardly to the limit of its movement along the shaft 16 against the pressure of the spring 26' thereby permitting the knob 25 and its associated dial member 26 to be rotated freely with respect to the dial member 24, and permit the pin 31 to be aligned with and inserted into any selected aperture e. When the pin 31 is engaged in any selected aperture e the numeral d associated with such aperture e will be visible through the window-like aperture g of the dial member 26.

The cradle 19 is provided with a handle 32 extending outwardly from the lower portion of the leg 18 through the aperture 23. By manual operation the cradle 19 may be optionally rocked downwardly (as shown in dotted lines in Figure 4) carrying the shaft 16 therewith and thus disengaging the gears 14 and 15. When the cradle 19 has been rocked into its upper or engaged position, it is maintained therein, during operation of the machine A, by a detent plunger 33 biased outwardly by a spring 34, into a detent recess 34' formed in the rear face of the leg 18.

Formed integrally with the forward wall of the housing 3 is a hollow boss 35 opening at its lower end upon the upper transverse margin of the aperture 23 and having disposed therein a spiral spring 36 in endwise abutment against the upper end-face of the leg 18 for biasing the cradle 19 downwardly into disengaged position when the detent plunger 33 is released, as will presently be more fully described. Mounted encirclingly on and secured at its inner end to the shaft 16 between the gear 15 and leg 18 is a spiral spring 37, and between the gear 15 and leg 17 there is keyed on the shaft 16 a disk or cam member 38 provided in its periphery with a recess 39 for engagement with the inner end or tongue 40 of a rearwardly extending plunger-like rod 41 extending through a cylinder-like guide 42 integral with the wall 4. Adjacent the tongue 40, the rod 41 is provided with a plunger-like head 43 sized for sliding engagement along the walls of the guide 42. Disposed within the cylinder-like guide 42 is a spiral spring 44 encircling the rod 41 and in endwise abutment against the inner face of the plunger-like head 43 and the end-face of the guide 42. At its projected or rearward end the rod 41 is secured by a pin 45 to a relatively short connecting link 46, which, in turn, is connected by a pin 47 to a link 48, which, in turn, is connected by a pin 49 to a rod section 50 projecting rearwardly through a guide 51 integral with and extending forwardly from the wall 8 of the housing 3. The rod 50 is provided on its outer end with cap member 52 diametrically larger than the rod 50 for limiting inward movement thereof.

Formed integrally with the rod 50 adjacent its forward end is an L-shaped member 53 having an upstanding inverted yoke 54 for engagement between the collars 13, 13' of the driven member 9. Encircling the rod 50 in endwise abutment against the L-shaped member 53 and inner

face of the guide 51 is a spiral spring 55. Integral with the link 48 is an upstanding lever arm 56 projecting through a suitable aperture in the upper wall of the housing 3 and being provided on its projected end with a handle 56'.

The ratio between the worm 14 and the worm gear 15 is such that the shaft 16 and its associated dial members 24, 26 will be rotated through the arcuate distance between the centers of two adjacent apertures e or one "unit" as it may be called for each revolution of the shaft 10. Furthermore, the cam 38 is pinned to the shaft 16 in such position relative to the dial 26, that when the pin 31 is inserted into the "zero" aperture and allowed to come to rest stop-wise against the lateral face of the cradle-leg 18, the recess 39 of the cam 38 will be in "zero" position opposite the tongue 40. If it is desired, for example to set the armature winding machine A for a three turn winding, the knob 25 is pulled outwardly and the dial members 24, 26 manually rotated so that the pin 31 will drop into the aperture e which is labeled with the numeral "three." This relative rotational movement tends to "wind-up" the spiral spring 37 and when the knob 25 is released again the shaft 16 and its associated elements will rotate until the pin 31 stops against the lateral face of the cradle-leg 18; and the cam recess 39 will be shifted arcuately three "units" away from its "zero" position. Thus when the clutch members 6, 9 are engaged and the shaft 10 makes three complete revolutions the cam recess 39 will have moved opposite the tongue 40, and the latter will move therewith causing the links 46, 48, the rod 50, and the yoke 54 to shift under influence of the springs 44, 55 and the driven clutch member 9 will be disengaged from the driving clutch member 6.

Between the tongue 40 and plunger-like head 43 on the rod 41 there is mounted a collar 57 having integral therewith a depending pin 58 disposed between the opposed legs 59, 59' of the bifurcated end of an angular lever arm 60 pivotally mounted, approximately intermediate its length, on a lug 61 integral with and projecting from the wall 4. Adjacent its other end, the arm 60 is secured to a relatively short T-shaped member 62 about the leg of which the spring 34 is disposed.

Rigidly mounted on the projected portion of the shaft 10, adjacent the housing 3, is a hand wheel 63, provided as an auxiliary manual means for rotating the shaft 16. Also rigidly mounted on the shaft 10 adjacent to, and projecting beyond the free end thereof, is a jaw-forming member 64 having a concave face 65 provided with a radially projecting axial tongue 65' for position-determining engagement in the slots of an armature R when mounted in the jaw member 64 for winding operation. Mounted on the side faces of the jaw member 64, adjacent to the forward margins thereof, are guide wings 66 for directing the wire w from spools s into the particular armature slots presented for winding.

Shiftably mounted in a bearing 67 secured at the forward end of the table 1 is a slide rod 68 axially bored for rotatably supporting a stub-shaft 69 which projects axially outwardly from the rod 68 and is rigidly provided at its end with a jaw-forming V-block 70 adapted for co-operation with the jaw member 64, being normally urged outwardly by a spiral spring 71 mounted encirclingly about the projecting end of the stub-shaft 69 in endwise abutment between the V-block 70 and the end face of the rod 68. The

rod 68 extends through the bearing 67 and at its other end is provided with a link 72 pivotally secured by a pin 73 which projects upwardly for retentive engagement with one end of a toggle-spring 74, the other end of which is engaged by a pin 75 secured in a slide-block 76. The link 72 is pivotally connected at its forward end to a toggle link 77, which is, in turn, pivoted upon the slide block 76 rearwardly of the pin 75. Formed preferably integrally with, and projecting laterally from, the toggle link 77, is an operating handle member 78, and the toggle link 77 is finally provided with a shoulder 79 for stop-wise abutment against a stop pin 80 fixed in the bearing 67. The stop pin 80 is located so that the toggle link 77 will be held releasably locked thereagainst by the toggle action of the spring 74, as may best be seen in Figure 1.

The slide block 76 is provided on its under face with an under-cut slide 81 for movement within a complementarily designed slide way 82 provided in the upper face of an extension arm 83 of the bearing 67. The end face of the slide block 76 is provided with an internally threaded aperture for receiving the end of an adjustment screw 84 threadedly mounted in and extending through a flange 85 on the end of the arm 83. A handle 86 is provided on the extended portion of the screw 84.

In use the operator will swing the handle 78 outwardly toward himself and thence to the right drawing the shoulder 79 of the toggle link 77 away from the stop pin 80 and as soon as the link 72 and the toggle link 77 have traveled to the forward side of dead-center, the toggle spring 74 will contract and the slide rod 68 together with the jaw-forming V-block 70 supported thereby, will be shifted to the right, away from the jaw member 64 an armature R may then be placed within the jaw member 64 so that one of its slots engages the tongue 65' and thereupon the handle member 78 may be shifted to original position, moving the jaw-forming V-block 70 toward the jaw member 64 for holding the armature R firmly in place. The handle 86 may then be turned to urge the slide block 76 forwardly increasing the tension of the toggle spring 74 and preventing any unauthorized releasing movement of the handle 78.

The armature R will be held in such position that two diametrically opposite slots lie in a vertical plane directly in line with the wire guiding wings 66. The wires w are then manually pulled downwardly from the spools s and fixed in place on the armature core in the conventional manner.

The knob 25 is then pulled outwardly compressing the spring 26' and is then revolved so that the number on the face of the dial member 24 corresponding to the number of turns desired to be made about the armature R appears through the window-like aperture g in the dial face 26, the knob 25 is then released for movement inwardly into the surface abutment against the dial member 24, whereupon the pin 31 will extend through the selected aperture e in the dial member 24. By this setting procedure the shaft 16 is rotated putting a tension on the spring 37 and positioning the cam member 38 so that the recess 39 is withdrawn from alignment with the tongue 40 of the rod section 41 a distance commensurate with the number of turns desired. It is, of course, apparent, that, if necessary, prior to such rotation of the shaft 16, the handle 56' is pulled rearwardly so as to withdraw the tongue 40 of the rod section 41 from

the recess 39, as may best be seen in Figure 13, so that the cam member 38 may be moved. Upon effecting the desired setting, the tongue 40 abuts against the peripheral face of the cam member 38 as may best be seen in Figure 10. The handle 56' is then pulled forwardly straightening the links 46, 48, and causing the rod section 50 to slide rearwardly in the guide 51 as abutment of the tongue 40 against the cam member 38 prevents forward movement. Thereupon the L-shaped member 53 is moved rearwardly causing the yoke 54 to abut against the inner face of the collar 13 whereby the clutch forming driven member 9 engages the clutch-forming driving member 6 as may best be seen in Figure 11. The shaft 10 is thus rotated whereby the worm gear 14 drivingly meshes with the spur gear 15, rotating the shaft 16 with the cam-member 38 thereon. As the recess 39 rotates into alignment with the tongue 40 of the rod section 41, the end 40 snaps, as it were, into the recess 39 preventing further rotation of the shaft 16, as may best be seen in Figure 12. Thereon the rod 50 slides forwardly, causing the yoke 54 in co-operation with the collar 13' to shift the clutch-forming driven member 9 out on engagement with the member 6 thereby arresting rotation of the shaft 10. The number of turns of wire w desired for the armature R will then have been effected.

When the tongue 40 of the rod section 41 springs into the recess 39 at the completion of the operation, the pin 53 is carried forwardly and into abutment against the leg 18 of the bifurcated-end of the arm 60 whereby the arm 60 is pivoted and the outer end thereof is rocked rearwardly releasing the detent plunger 33 from the notch 34'.

Since the tongue 40 is still engaged in the recess 39, however, the cradle 19 will remain substantially in upwardly swung or "engaged" position but there is sufficient play between the tongue 40 and the cam-recess 39 to permit the cradle 19 to drop a short distance sufficient to 45 displace the detent notch 34' downwardly from the detent plunger 33 under influence of the spring 36.

By withdrawing the jaw-forming V-block 70 as described above, the armature R may be manually turned in order to present another pair of slots in alignment with the wings 66 for winding operation. After the armature R has been thus reset, the handle 56' is swung rearwardly, and since the spring 55 is substantially stronger than the spring 44 the links 46, 48 will break upwardly, so to speak, as shown in Figure 13 and the tongue 40 will be withdrawn from the recess 39 of the cam 38 allowing the cradle 19 to drop all the way down to its lowermost position. It should be noted in this connection that the retractive movement of the tongue 40 will swing the arm 60' back to original position restoring spring bias upon the detent plunger 33 but since the detent notch 34' has already been shifted down out of alignment therewith by reason of the initial movement of the cradle 19, the detent plunger 33 will not interfere with the downward dropping movement of the cradle 19.

As the cradle 19 drops down the worm gear 15 will become disengaged from the worm 14 and the shaft 16 being thus released will rotate reversely under influence of the spiral spring 37 until the stop pin 31 abuts against the stop-forming side face of the cradle-leg 18 returning

the cam 38 to initial position ready for the next winding cycle.

The next winding cycle may be initiated by lifting the handle 32 and thereby swinging the cradle 19 upwardly again to "engaged" position, whereupon the detent plunger 33 will re-engage the detent notch 34 holding the cradle in such "engaged" position against the downward bias of spring 36. Meanwhile the tongue 40 will ride against the periphery of the cam 38 and the plunger-like rod 41 will be held in "disengaged" position against the bias of the spring 44. When the cradle 19 is lifted into "engaged" position, the worm-gear 15 and the worm 14 are thus re-engaged. Because there may be a slight amount of over travel of the shaft 10 and handwheel 63 the worm gear 15 and worm 14 may not be exactly aligned for meshing engagement, in which case the operator merely rotates the hand wheel 63 until a portion of alignment is reached. In fact this latter manual operation is desirable to permit the operator to start each series of turns from a selected initial position on the armature. Thereupon the handle 56 may be shifted forwardly as above described and the driven member 9 coupled to the driving member 6 so that the shaft 10 will resume rotation.

It should be understood that changes and modifications in the form, construction, arrangement, and combination of the several parts of the armature winding machine may be made and substituted for those herein shown and described without departing from the nature and principle of my invention.

Having thus described my invention, what I claim and desire to secure by Letters Patent is:

1. For use with armature winding machines and the like, a turn-counting transmission comprising a driving shaft, a driven shaft, a clutch optionally connecting the driven shaft to the driving shaft, a countershaft driven in timed relation to the driven shaft, a wheel pinned to the countershaft and having a recess formed in the periphery thereof, a first rod shiftably mounted adjacent to said wheel and spring biased for engagement in said recess when the wheel is rotated to a selected position, a second rod slidably mounted in axial alignment with the first rod, a pair of pivotally connected toggle links operably connected to the opposed ends of the first and second rod, means rigidly connected to the second rod for disengaging said clutch when the second rod is shifted, handle means rigidly connected to one of said toggle links for permitting said links to be manually actuated from a position of axial alignment with said first and second rods to a position respectively at angles to the longitudinal axes of said first and second rods whereby the first link may be disengaged from the recess of the wheel independently of movement of the second rod and the second rod may be shifted to reengage the clutch without imparting longitudinal shifting movement to the first rod.

2. For use with armature winding machines and the like, a turn-counting transmission comprising a driving shaft, a driven shaft, a clutch optionally connecting the driven shaft to the driving shaft, a countershaft driven in timed relation to the driven shaft, a wheel pinned to the countershaft and having a recess formed in the periphery thereof, a spring biased rod shiftably mounted adjacent to said wheel for engagement in said recess when the wheel is rotated to a selected position, a second rod slidably mounted

in axial alignment with the first rod, a pair of pivotally connected toggle links operably connected to the opposed ends of the first and second rod, means rigidly connected to the second rod for disengaging said clutch when the second rod is shifted axially in the direction of the wheel, handle means rigidly connected to one of said toggle links for permitting said links to be manually actuated from a position of axial alignment with said first and second rods to a position respectively at angles to the longitudinal axes of said first and second rods whereby the first link may be disengaged from the recess of the wheel independently of movement of the second rod and the second rod may be shifted to reengage the clutch without imparting longitudinal shifting movement to the first rod.

3. For use with armature winding machines and the like, a turn-counting transmission comprising a driving shaft, a driven shaft, a clutch optionally connecting the driven shaft to the driving shaft, a countershaft driven in timed relation to the driven shaft, a wheel pinned to the countershaft and having a recess formed in the periphery thereof, a spring biased rod shiftably mounted adjacent to said wheel for engagement in said recess when the wheel is rotated to a selected position, a second spring biased rod slidably mounted in axial alignment with the first rod, a pair of pivotally connected toggle links operably connected to the opposed ends of the first and second rod, means rigidly connected to the second rod for disengaging said clutch when the second rod is shifted axially in the direction of the wheel, handle means rigidly connected to one of said toggle links for permitting said links to be manually actuated from a position of axial alignment with said first and second rods to a position respectively at angles to the longitudinal axes of said first and second rods whereby the first link may be disengaged from the recess of the wheel independently of movement of the second rod and the second rod may be shifted to reengage the clutch without imparting longitudinal shifting movement to the first rod.

4. For use with an armature winding machine and the like, a turn-counting transmission comprising a driving shaft, a driven shaft, optionally engageable clutch forming elements respectively connected to the driven shaft and the driving shaft, said driving shaft and driven shaft being connected through the clutch members when said clutch members are engaged and being disconnected when the clutch members are disengaged, a shifter arm operatively connected to one of said clutch members for moving it into and out of engagement with the other clutch member, a worm pinned to the driven shaft, a cradle swingably mounted in proximate relation to the worm, a stub shaft journaled in and carried by the cradle, a gear pinned to the stub shaft in position for engagement with the worm when the cradle is swung toward the driven shaft, said cradle normally being biased toward a position away from such engaged position, locking means for holding the cradle in such engaged position, a cam-like member pinned to the stub shaft and having a single radial slot, a plunger shiftably mounted for movement toward and away from the cam-like member along a path radial with respect thereto and having a tongue-like element adapted for optional engagement in the slot of the cam-like member, said plunger being normally biased toward the cam-like member so that its tongue-like element will enter into

and engage the slot whenever the slot is positioned in radial alignment with the tongue-like element, means for connecting the plunger and shifter arm so that the latter is pulled into clutch-disengaged position when the tongue-like element is engaged in the slot and means actuated responsive to movement of the plunger for disengaging the locking means and thereby permitting the cradle to swing away from engaged position as the shifter arm comes into clutch-disengaged position so that as the clutch elements become disengaged the gear and worm will also become disengaged.

5. For use with an armature winding machine and the like, a turn-counting transmission comprising a driving shaft, a driven shaft optionally engageable clutch forming elements respectively connected to the driven shaft and the driving shaft, said driving shaft and driven shaft being connected through the clutch members when said clutch members are engaged and being disconnected when the clutch members are disengaged, a shifter arm operatively connected to one of said clutch members for moving it into and out of engagement with the other clutch member, a worm pinned to the driven shaft, a cradle swingably mounted in proximate relation to the worm, a stub shaft journaled in and carried by the cradle, a gear pinned to the stub shaft in position for engagement with the worm when the cradle is swung toward the driven shaft, said cradle normally being biased toward a position away from such engaged position, locking means for holding the cradle in such engaged position, a cam-like member pinned to the stub shaft and having a single radial slot, a plunger shiftably mounted for movement toward and away from the cam-like member along a path radial with respect thereto and having a tongue-like element adapted for optional engagement in the slot of the cam-like member, said plunger being normally biased toward the cam-like member so that its tongue-like element will enter into and engage the slot whenever the slot is positioned in radial alignment with the tongue-like element, means for connecting the plunger and shifter arm so that the latter is pulled into clutch-disengaged position when the tongue-like element is engaged in the slot and means actuated by the plunger for disengaging the locking means and thereby permitting the cradle to swing away from engaged position as the shifter arm comes into clutch-disengaged position so that as the clutch elements become disengaged the gear and worm will also become disengaged.

6. For use with an armature winding machine and the like, a turn-counting transmission comprising a driving shaft, a driven shaft, optionally engageable clutch forming elements respectively connected to the driven shaft and the driving shaft, said driving shaft and driven shaft being

connected through the clutch members when said clutch members are engaged and being disconnected when the clutch members are disengaged, a shifter arm operatively connected to one of said clutch members for moving it into and out of engagement with the other clutch member, a worm pinned to the driven shaft, a cradle swingably mounted in proximate relation to the worm, a stub shaft journaled in and carried by the cradle, a gear pinned to the stub shaft in position for engagement with the worm when the cradle is swung toward the driven shaft, said cradle normally being biased toward a position away from such engaged position, locking means for holding the cradle in such engaged position, a cam-like member pinned to the stub shaft and having a single radial slot, a plunger shiftably mounted for movement toward and away from the cam-like member along a path radial with respect thereto and having a tongue-like element adapted for optional engagement in the slot of the cam-like member, said plunger being normally biased toward the cam-like member so that its tongue-like element will enter into and engage the slot whenever the slot is positioned in radial alignment with the tongue-like element, means for connecting the plunger and shifter arm so that the latter is pulled into clutch-disengaged position when the tongue-like element is engaged in the slot, means actuated responsive to movement of the plunger for disengaging the locking means and thereby permitting the cradle to swing away from engaged position as the shifter arm comes into clutch-disengaged position so that as the clutch elements become disengaged the gear and worm will also become disengaged, and a spring operatively connected to the stub shaft and being adapted to be placed under increased tension as the stub shaft is rotated by the driven shaft through the engagement between the worm and gear, said spring being adapted to rotate the shaft in the opposite direction as the cradle swings out of engaged position.
